No. 36,732.

Patented January 12, 1904.

UNITED STATES PATENT OFFICE.

DANIEL F. PRINTZ, OF READING, PENNSYLVANIA.

DESIGN FOR A STOVE-DOOR.

SPECIFICATION forming part of Design No. 36,732, dated January 12, 1904.

Application filed December 10, 1903. Serial No. 184,681. Term of patent 14 years.

To all whom it may concern:

Be it known that I, DANIEL F. PRINTZ, a citizen of the United States, residing at Reading, in the county of Berks and State of Pennsylvania, have invented a new, original, and ornamental Design for Stove-Doors, reference being had to the accompanying drawing.

The illustration is a plan view of a stove-door, showing my design.

What I claim is—

The ornamental design for a stove-door, as shown.

DANIEL F. PRINTZ.
